ICE CREAM SANDWICH PACKAGE

James A. Duke, Atlanta, Ga., assignor to Rite Pack Company, East Point, Ga.

Application August 27, 1952, Serial No. 306,595

1 Claim. (Cl. 229—51)

This invention relates to a package for holding ice cream sandwiches.

An object of this invention is to provide a package or container for ice cream sandwiches which will not only facilitate the packing of the ice cream, but will also form a holder for use in eating of the sandwich.

Another object of this invention is to provide a package or container which may be formed from a blank sheet.

A further object of this invention is to provide a package or container which is so constructed and arranged that the wafers will be held against the inner faces of the side walls before the ice cream is inserted, and the holding means for the wafers will be forced outwardly by the ice cream as the latter is packed in the container.

A further object of this invention is to provide a container wherein the end walls have struck therefrom wafer holders which are initially bent inwardly to wafer holding position and are adapted upon filling the container with ice cream to be forced outwardly by pressure of the ice cream so as to thereby close the openings in the end walls.

With the above and other objects in view, my invention consists in the arrangement, combination and details of construction disclosed in the drawing and specification, and then more particularly pointed out in the appended claims.

In the drawing:

Figure 1 is a front elevation of a container for an ice cream sandwich constructed according to an embodiment of this invention.

Figure 2 is a side elevation of the device.

Figure 3 is a sectional view taken substantially on the line 3—3 of Figure 2 showing the container with the wafers in position for receiving the ice cream therebetween.

Figure 4 is a sectional view taken on the line 4—4 of Figure 3.

Figure 5 is a plan view of the blank container.

Referring to the drawing, the numerals 10 and 11 designate front and rear walls of a cardboard or fibrous container constructed according to an embodiment of this invention. The front wall 10 has formed integral therewith a bottom wall 12, which in the closed position of the container is adapted to extend between the front and rear walls 10 and 11, as shown in Figures 2 and 3.

A pair of side walls 13 and 14 are formed integral with the front and rear walls 10 and 11, respectively, and a closure or top wall 15 is formed integral with the side wall 13 and in the closed position of closure or top wall 15, the latter is disposed in the position shown in Figures 3 and 4.

The lower ends of the side walls 13 and 14 have extending inwardly therefrom bottom flaps 16 and 17, respectively, which overlie the upper side of the bottom wall 12. The bottom wall 12 is formed with a flap 18 which is insertable between rear wall 11 and a wafer 19.

In order to provide a means whereby a pair of wafers 19 and 20 may be initially supported in face abutting and

2

substantially contacting relation with the walls 11 and 10, respectively, the side walls 13 and 14 have struck therefrom a pair of flaps 21 and 22, respectively. These flaps 21 and 22 are initially adapted to be pressed inwardly when the container is empty to the position shown in Figure 3, and the wafers 19 and 20 are then inserted between the flaps 21 and 22 so that the outer edges of the flaps 21 and 22 will hold the wafers in upright parallel position. At the time the container is to be filled, closure or top wall 15 is raised upwardly to a substantially vertical position and after the wafers 19 and 20 are inserted in proper position, the partly frozen ice cream is pressed between the wafers 19 and 20. The filling of the space between the wafers 19 and 20 will cause the flaps 21 and 22 to swing downwardly and outwardly to a position substantially coplanar with the walls or sides 13 and 14.

In order to provide a means whereby the ice cream with the wafers 19 and 20 may be readily consumed, side wall 13 is provided with a downwardly inclined score or perforation 23 extending from the upper edge thereof, and the score 23 connects with an angled score 24 which is formed in the front wall 10. The angled perforation or score 24 also connects with a horizontal perforation or score 25 formed in the front wall 10 and perforation 25 connects with a horizontal perforation 26 formed in side wall 14. Horizontal perforation 26 in side wall 14 connects with a horizontal perforation 27 formed in rear wall 11. Side wall 13, as shown in Figure 5, is formed with a vertical flap 28 which is adapted to be bent inwardly to be disposed in contacting relation with rear wall 11, and flap 28 is adapted to be adhesively secured to the inner side of rear wall 11. Flap 28 is formed with a horizontal perforation 29, which is in alignment with perforation 27 and a score or perforation line 30 is formed in side wall 13. Perforation 30 is disposed in alignment with perforation 25 which, as shown in Figure 5, extends entirely across front wall 10. In the tearing of the container along the score lines hereinbefore set forth, the closure 15 is raised upwardly and is then slightly twisted so as to begin the tearing of the container along the score line or perforation 23. The container is then separated as to the upper separable portion which, as shown in Figure 5, is the larger portion of the container. The tearing of the upper portion of the container will expose the wafers 19 and 20, with the ice cream between the wafers being exposed at the opposite vertical edges of the wafers.

The lower portion of the container, indicated generally by the numeral 31, forms a holder for the sandwich as the latter is being consumed so that the sandwich can be readily consumed without losing any of the ice cream. After the container has been filled with ice cream, the top closure 15 may be swung downwardly so that the closure 15 will adhere to the cream as the latter is being frozen solid between the wafers 19 and 20. Preferably during the filling of the container or package, the container is disposed in a mold or receptacle having a size to readily receive the container.

The container hereinbefore described will provide an improved means whereby an ice cream sandwich can be easily and quickly formed and will eliminate the use of holders or separators for the wafers during the filling operation.

I do not mean to confine myself to the exact details of construction herein disclosed, but claim all variations falling within the purview of the appended claim.

What is claimed is:

A combination mold and container for an ice cream sandwich of the type having a body of ice cream interposed between a pair of wafers, comprising a pair of spaced apart side walls, opposite end walls, a bottom wall hingedly secured to one of said side walls, a tongue

formed on the free end of said bottom wall, and a top wall hingedly secured to one of said end walls, each end wall having a flap struck therefrom approximately equidistant from the top and bottom edges thereof, said flap being connected at its upper horizontal edge with said end wall and each flap being initially bendable inwardly to a wafer holding position, the opposite vertical edges of each flap being spaced from said side walls whereby a pair of wafers may be inserted between said flaps and said side walls, said flaps, upon filling of the space between the wafers with partially frozen ice cream, swinging outwardly to alignment with said end walls, said side and said end walls having aligned horizontal perforations with the perforations on said end walls extending to each side edge of said struck out flap, one side wall and one end wall having an inclined perforation connecting with said

5 horizontal perforations, whereby the container may be divided and an upper portion torn from a lower portion.
